UNITED STATES PATENT OFFICE

2,323,858

RADIO RECEIVING SYSTEM

Albert Le Roy Upton, St. Louis, Mo.

Application July 31, 1942, Serial No. 453,124

3 Claims. (Cl. 179—1)

This invention relates to radio receivers.

An object of the invention is to provide means whereby an audio-frequency circuit in a receiver may be used simultaneously or selectively to actuate a loud speaker and actuate a secondary circuit for the purpose of producing a recording, operating a public address system or rebroadcast. That is to say, a monitor loud speaker may be used to receive a radio broadcast, and then by manipulation the actuating circuit for the loud speaker can, at the will of the operator, influence a secondary circuit for the purposes indicated. The arrangement is such that the loud speaker may be cut out, if desired, and when cut out the operation is quiet. These objects and the construction and operation of the system will be apparent from the following detailed description taken in connection with the accompanying drawing.

The drawing is a circuit diagram of a system embodying the invention.

The speaker circuit 1 includes the secondary coil 2 of a transformer 3, the voice coil 4 of a loud speaker, and the primary coil 5 of a transformer 6. The primary 7 of the transformer 3 is in a circuit from an audio amplifier. It will be understood that the arrangement as described, apart from the transformer 6 and its primary 5, is of conventional design and is such as is commonly used in radio receivers. By reason, however, of the transformer 6 in the circuit 1 this circuit is used to operate a remote public address system, a recorder, or as an input for a rebroadcast.

The coils 2, 4 and 5 are matched. As an example, each may have an inductance of 2 ohms. For theoretical ideal operating conditions one only of the coils 4 and 5 will be in the circuit effectively at a time, but practically both of them can be in circuit simultaneously without affecting the results.

A three-way switch 8 is operable to by-pass either coil 4 or 5 selectively at will. Thus when the switch is closed on terminal 9 the voice coil 4 is by-passed, but when it is closed on the terminal 10 the coil 5 is by-passed. When the switch is in neutral position 11, both coils 4 and 5 are in circuit.

The secondary of the transformer 6 is in a circuit 12 which also includes the primary of a transformer 13. In this circuit the secondary of the transformer 6, and the primary of the transformer 13, are matched.

The secondary of the transformer 13 is in a circuit 14 supplying the input for a recorder or 55

pre-amplifier, whereby signals carried by the circuit 1 may be used for secondary, public address or rebroadcast.

The coils of the transformer 6 and 1 which are in the circuit 12 should have matched impedance.

A jack 15 across the circuit 12 accommodates a plug 16 connected to a visual indicator 17, by which the amplitude of the signal can be read.

A constant impedance attenuator 18 is placed across the circuit 14, by which the amplitude of the signal fed through that circuit may be controlled.

In using the system, the speaker can be employed as a monitor. When the broadcast is first received through the speaker the switch 8 will be closed on the terminal 10, shunting the coil 5. Then when the reception indicates it should be relayed to the remainder of the system, the switch is moved to the terminal 9 or neutral position 11.

If it is desired to retain the speaker in service, the switch will be moved to neutral position, by which the speaker coil 4 and the transformer coil 5 will be in series. Even though theoretically this is not the ideal condition, satisfactory service is obtained. For perfect performance, however, the switch is moved to the terminal 9, shunting the coil 4, as soon as the speaker can be eliminated. Because of the arrangement of the switch 8 in the circuit, with its three positions as shown, it can be moved from any position to the other without any audible click either in the speaker or the auxiliary part of the system.

The circuit 14 may feed any desired reproduction system, as for instance a theatre sound system illustrated and described in my copending application filed on the same date herewith.

It will be obvious that various changes may be made in the details of construction, within the scope of the appended claims, without departing from the spirit of this invention. Parts of the invention may be used without the whole and improvements and additions may be made thereto while retaining the essence of the invention.

I claim:

1. In a radio receiver, a circuit fed from an audio amplifier, a speaker circuit connected with the first mentioned circuit through a transformer having a primary coil in the first mentioned circuit and a secondary coil in the speaker circuit, a voice coil for a speaker and a primary coil of a second transformer in series in said speaker circuit with the aforementioned secondary coil, a switch arranged to selectively by-pass either said

voice coil or said primary coil of the second transformer, and a feed circuit for a reproduction system including a secondary coil of said second transformer.

2. In a radio receiver, a circuit fed from an audio amplifier, a speaker circuit connected with the first mentioned circuit through a transformer having a primary coil in the first mentioned circuit and a secondary coil in the speaker circuit, a voice coil for a speaker and a primary coil by a second transformer in series in said speaker circuit with the aforementioned secondary coil, a feed circuit for a reproduction system, including a secondary coil of said second transformer, and a constant impedance attenuator for controlling the amplitude of the signals from said feed circuit.

3. In a radio receiver, a circuit fed from an audio amplifier, a speaker circuit connected with the first mentioned circuit through a transformer having a primary coil in the first mentioned circuit and a secondary coil in the speaker circuit, a voice coil for a speaker and a primary coil by a second transformer in series in said speaker circuit with the aforementioned secondary coil, a feed circuit for a reproduction system including a secondary coil of said second transformer, and a visual indicator in the feed circuit by which the amplitude of the signals in said circuit may be read.

ALBERT LE ROY UPTON.
